US0D1062864S

(12) **United States Design Patent** (10) **Patent No.:** **US D1,062,864 S**
(45) **Date of Patent:** ** *Feb. 18, 2025

(54) **MICROFIBER BOOKLET**

(71) Applicant: **Medline Industries, LP**, Northfield, IL (US)

(72) Inventors: **Megan Henken**, Wauconda, IL (US); **Steve McNabb**, Kenosha, WI (US)

(73) Assignee: **Medline Industries, LP**, Northfield, IL (US)

(*) Notice: This patent is subject to a terminal disclaimer.

(**) Term: **15 Years**

(21) Appl. No.: **29/846,976**

(22) Filed: **Jul. 20, 2022**

(58) **Field of Classification Search**

CLAIM

The ornamental design for a microfiber booklet, as shown and described.

DESCRIPTION

FIG. 1 is a perspective view of a microfiber booklet, showing our new design;

FIG. 2 is a front elevation view thereof;

FIG. 3 is a front elevation view of the microfiber booklet folded to an open position between a first microfiber sheet and a second microfiber sheet;

FIG. 4 is a front elevation view of the microfiber booklet folded to an open position between the second microfiber sheet and a third microfiber sheet;

FIG. 5 is a front elevation view of the microfiber booklet folded to an open position between the third microfiber sheet and a fourth microfiber sheet;

FIG. 6 is a front elevation view of the microfiber booklet folded to an open position between the fourth microfiber sheet and a fifth microfiber sheet;

FIG. 7 is a rear elevation view of the microfiber booklet folded to the open position between the second microfiber sheet and the third microfiber sheet;

FIG. 8 is a rear elevation view of the microfiber booklet;

FIG. 9 is a top plan view thereof;

FIG. 10 is a bottom plan view thereof;

FIG. 11 is a right side elevation view thereof; and,

FIG. 12 is a left side elevation view thereof.

The evenly spaced broken lines are directed to environment and form no part of the claimed design. The dot-dash broken lines represent the bounds of the claimed design and form no part of the claimed design.
